UNITED STATES PATENT OFFICE

OTTO L. MOELLER, OF MOBILE, MISSOURI

AWNNG CONSTRUCTION

Application filed March 21, 1930. Serial No. 437,865.

This invention relates to certain new and useful improvements and structural refinements embodied in a novel awning and retaining means therefor.

In carrying the invention into practice, I have evolved and produced a structure which is characterized by numerous structural distinctions mechanically co-ordinated in a manner to facilitate raising, lowering and retaining of the awning in an extended state as well as in a folded or contracted state.

My primary aim is to generally improve upon constructions in the prior art by providing a new organization of parts which are coherently related in a manner to form a marked advance and readily distinguishable contributions to the prior art.

The specific elements and their association and arrangement will become more readily apparent from the following description and drawings.

In the drawings:

Figure 1 is an elevational view of a screen equipped window frame showing the improved awning construction mounted thereon, and devised in accordance with the present invention.

Figure 2 is a side elevational view of the structure seen in Figure 1.

Figure 3 is a horizontal section on the line 3—3 of Figure 1.

Figure 4 is a view like Figure 2 showing the awning folded to an out of the way, ineffective position.

Figure 5 is a view showing the adjustable coupling for the swingable frame.

Figure 6 is an elevational view of one of the details.

Figure 7 is a section on the line 7—7 of Figure 1.

Figure 8 is a vertical detail section on the line 8—8 of Figure 1.

Figure 9 is a detail section showing the spring anchoring means.

Figure 10 is a view showing the toothed retaining means for the lower end portion of the awning.

In the drawings, the reference character 11 designates generally the window frame, and 12 designates the screen. The canvas 13

forming the awning material is of suitable construction and has its upper end fastened to the frame as indicated in Figures 1 and 3. Incidentally, I call attention to the fact that the various details of this arrangement are made in sections for companion relationship to facilitate adjustment to different sizes of windows.

For instance, the numerals 14 designate the complementary section which form attaching plates for anchoring the upper edge portion of the awning material on the frame. The fact is, as seen in Figure 3, the awning material is fastened by screws or the like to the turnbuckle element 15. These in turn are screwed to a plate 16 bearing against the wooden frame and these parts 15 and 16 are held in place by the bent edge portion of the two plates 14. The element 15 includes screw threaded shank portions for accommodating the adjusting or coupling sleeve 17. This permits the sectional anchoring means to be adapted to different sizes of window frames. It also permits the canvas to be removed whenever necessary or desired for replacement and repair purposes.

The numerals 18 designate a pair of attaching brackets whose leg portions are fastened to the intermediate portions of the vertical bars of the window frame. Each bracket includes a channel-shaped portion 19 having a pivot pin 20 therein. These two brackets 18 serve to accommodate swingably mounted U-shaped frames 21. This frame is composed of a plurality of adjustably connected sections. For instance, the numerals 22 designate connecting members having their inner end portions formed with slots 23. These slots engage the pins 20 and are adapted to assume either the position represented in Figure 2 or the contracted retaining position represented in Figure 4.

Then there are two L-shaped sections 24 having extensible connections with the connectors 22 and having their front ends joined together by an adjustable connecting strip 25 as represented in Figure 5. It follows that this U-shaped frame 21 comprises a pair of L-shaped members 24 whose short arms are adjustably connected with the connector 100

members 22 and whose long arms at the front are connected together by the adjustable strip 25.

I wish to call attention to the fact that the sections 24 are of channel-shaped cross sectional form so as to accommodate a coiled awning retention spring 26. This spring is seated in the channel and has its end coil or eye 27 anchored on the lugs 28, one of these being shown in Figure 9.

The lower end portion of the awning material is seated in the front channel and clamped therein by the coiled spring. The doubled portion 29 is also held in place by this spring as is the depending apron or ornamental fringe 30. This provides a suitable and practical releasable connection of the lower fringed ends of the awning with the U-shaped frame 21.

The pin and slot connection 20 and 23 affords a desirable connection between the frame 21 and the brackets 18 permitting the frame to be arranged in the right angular extended awning supported position seen in Figure 2 or to permit the frame to be folded up against the window frame structure as seen in Figure 4. When in the latter position, the slotted ends of the connector members 22 drop down into the channel-shaped portions 19 of the brackets 18 thus folding the entire structure in a relaxed state.

The upper edges of the front portions of the frame 21 are formed with serrations defining retention teeth 31 as seen in Figures 8 and 10 to aid in holding the awnings 13 against slippage.

On each side of the window frame is a relatively fixed channel-shaped guide 32 which serves to accommodate a slide 33 held in different adjusted positions by the bolt 34 and its accompanying thumb nut 35 (see Figure 7). The stay link 36 is pivotally connected at its lower ends of the slide and at its upper end to an apertured ear on the connecting elements 22. Incidentally this connecting element has a pin and slot connection with the adjacent portion of the frame structure 21.

Briefly, the structural features of this improved arrangement are as follows: Starting with the upper part of the structure, it will be seen that the adjustable plates 14 and the accompanying turnbuckle structure is a novel way of fastening the awning detachably and adjustably to the window frame. Secondly, the U-shaped frame member 21 composed of the adjustably connected sections and having pin and slot connection with the attached brackets 18 on the window frame is of importance.

Then too, the channel-shaped formation of the L-shaped members thereof to accommodate the coiled clamping spring for the lower end portion of the awning is a noticeable point. Particularly however, do I wish to

emphasize the pin and slot connection between the connectors 22 and the brackets 18 which allows the brackets to fold down into the channel-shaped portions 19 to permit the frame to take either of the positions represented in Figures 2 or 4 respectively. 70

Moreover, the bracing means comprising the link 36 connected to elements 22 and adjustably connected with the slides 33 in the channel-shaped attaching members 32 is of 75 advantage. I further call attention to the flexible cord 37, there being a pair of these provided, and each one connected at its outer end to the member 22 and having its intermediate portion passing over a pulley 38 on the frame and having its inner end portion provided with a finger ring or the like 39. These cords permit the frame 21 to be elevated from the interior of the window so as to permit the complete awning structure to be 80 folded expeditiously.

It is thought that persons skilled in the art to which the invention relates will be able to obtain a clear understanding of the invention after considering the description in connection with the drawings. Therefore, a more lengthy description is regarded as unnecessary. 85

Minor changes in shape, size, and rearrangement of details coming within the field 90 of invention claimed may be resorted to in actual practice if desired.

I claim:

1. In a structure of the class described, in combination, a window frame, an awning attached at its upper end to the frame, a substantially U-shaped supporting frame, the lower end of the awning being in connection with the bight portion of said U-shaped frame, brackets on said window frame, folding pin and slot connections between the U-shaped frame arms and said brackets, depending stay links pivotally connected with the intermediate portions of the arms of said U-shaped frame, and means adjustably connecting the lower ends of said stay links with the window frame, comprising channel-shaped attaching plates and slides adjustably mounted in the channel portions of said plates. 100

2. In a structure of the class described, in combination, a window frame, an awning attached at its upper end to the frame, a substantially U-shaped supporting frame, the lower end of the awning being in connection with the bight portion of said U-shaped frame, brackets on said window frame, folding pin and slot connections between the U-shaped frame arms and said brackets, depending stay links pivotally connected with the intermediate portions of the arms of said U-shaped frame, and means adjustably connecting the lower ends of said stay links with the window frame, comprising channel-shaped attaching plates and slides adjustably 110 mounted in the channel portions of said plates. 115

mounted in the channel portions of said plates, a pair of pulleys mounted on the window frame above the brackets, pull cords connected at their outer ends with the intermediate portions of the arms of said U-shaped frame, the intermediate portions of said cords passing over said pulleys to the interior of the window frame and the terminal ends being provided with finger rings, whereby to permit said U-shaped frame to be elevated by drawing said cords inwardly over the pulleys.

In testimony whereof I affix my signature.

OTTO L. MOELLER.
